G. GLAUDEL

WINDSHIELD ATTACHMENT

Filed March 8, 1922

INVENTOR:

GEORGE GLAUDEL,
BY: Otto de. Ruyge,
his Atty.

UNITED STATES PATENT OFFICE.

GEORGE GLAUDEL, OF LOS ANGELES, CALIFORNIA, ASSIGNOR TO BEN F. FOREST, OF LOS ANGELES, CALIFORNIA.

WINDSHIELD ATTACHMENT.

Application filed March 8, 1922. Serial No. 542,087.

To all whom it may concern:

Be it known that I, GEORGE GLAUDEL, a citizen of France, residing at Los Angeles, in the county of Los Angeles and State of California, have invented a new and useful Windshield Attachment, of which the following is a specification.

This invention relates to devices attached to the wind-shield of vehicles for supporting shading shields.

One of the objects of this invention is to provide a simple attachment that can be used on different vehicles without requiring material changes of a standard attachment.

Another object is to provide a device that embodies a standard size shading shield, and embodies also attaching means that will fit different vehicles.

Another object is to provide a device that embodies a standard size shading shield, and embodies also attaching means that will fit over the normal wind-shields of automobiles, having adjusting means that allow an adjustment to the width of the different wind-shields.

Another object is to provide a shield that can be attached over the existing wind-shields of automobiles, having means for adjustment in a vertical direction on the framework of the existing wind-shields, having other means for adjustment in a horizontal direction in relation to the width of the wind-shields to overcome the differences in this direction, and having other adjustments for holding the shading shield in desired relation to the existing wind-shields in front of such shields.

Other objects will appear from the following description and appended claim as well as from the accompanying drawing, in which—

Fig. 1 is a perspective front view of the device, a wind-shield of an automobile being indicated in dotted lines to illustrate the relative position of the device to the wind-shield of an automobile.

Fig. 2 is an end elevation of the supporting arm and the clamping member on one end of the device.

Fig. 3 is an end view of the clamping member in slightly enlarged scale, as seen in the direction of the arrow 3 in Fig. 2.

Fig. 4 is a front elevation of a clamping member.

The uprights 5 of the framework of a wind-shield of an automobile, indicated in dotted lines in Fig. 1, are normally designed to hold plain plate-glass, to protect the driver and the passengers in the automobile. Intense sunshine, or the bright and glaring headlights of other, approaching vehicles, however, are liable to irritate or affect the driver in steering the automobile.

On more expensive, and newer types of automobiles, provisions have been made and embodied in the construction to overcome such outside lights and effects.

It is therefore one of the objects of this invention to provide an attachment that may with advantage be used in cases where no provisions were made in the original construction.

The clamping members 6 and 7 are therefore preferably made to engage over the standards 5 of the framework of the existing wind-shield. The clamping members 6 and 7 are illustrated in detail in Figs. 3 and 4, being held together by the bolts 8. The engaging ends of the clamping members are provided with claw-like members 9, of shapes to fit over flat or round bars, the flat bars to be in alignment with the line of division between the two clamping members or at right angles to the line of division. The clamping member 6 is provided with an upwardly projecting lug 10 with a perforation 11. An upright member or supporting arm 12 is adjustably secured to each of the clamping members 6. The lower end of the supporting arm is made in form of a slotted bar or portion 14. The upper end of the supporting arm 12 is provided with a pivot 15 for supporting a shading shield 16. The shading shield is preferably made of a standard width between the uprights or supporting arms 12.

The bolts 13 in the lugs of the clamping members 6 are illustrated in the slotted portions of the supporting arms 12 nearly in middle position in the illustration of Fig. 1.

Since the wind-shields of automobiles vary very much, the uprights 5 being sometimes closer together and at other times further apart, it becomes essential that provisions be made to allow an attachment of the standard shading shield to the different wind-shields. From the illustration in Fig. 1, it will be clear that the wind-shield may be narrower or wider than shown and still

make the device applicable, since the clamping members can be moved sidewise in relation to the supporting arms 12 by means of the slotted portions of the supporting arms.

5 Connecting bars or members 16 are pivotally connected to the supporting arms 12, as indicated at 17. The members 16 are preferably slotted, to allow a setting of the shading shield in desired relations to the 10 wind shield by means of set screws 19, the slots being indicated at 18.

From the illustration in Fig. 2 it will be clear that the supporting arms 12, and thereby the whole device is arranged and 15 designed so that the shading shield becomes located in front of the wind shield, so that the whole device can be adjusted in an up and downward direction by means of the 20 clamping members on the framework of the wind shield.

Having thus described my invention, I claim:

In a shading shield, a pair of clamping members at each end of the shading shield 25 for engaging with the uprights of the frame-

work of the wind shield of an automobile, one of the members in each pair having a lug projecting upwardly, a shading-shield proper, the shading shield proper being of standard width and nearly equal to the 30 width of the wind-shield, a supporting arm pivotally engaged at each end with the shading shield proper, each arm having a slotted portion in its lower end forming in conjunction with the lug of the clamping members the adjusting means for the standard 35 sizes shading shield so as to make the standard shading shield applicable to the wind-shields of different widths, and securing means inserted through the slotted portions 40 of the supporting arms and the lugs of the clamping members.

In testimony that I claim the foregoing as my invention I have signed my name in the presence of two subscribing witnesses.

GEORGE GLAUDEL.

Witnesses:

O. H. KRUEZER,
JESSIE A. MANOCK.
